US0D1092957S

(12) United States Design Patent (10) Patent No.: US D1,092,957 S
(45) Date of Patent: * Sep. 16, 2025

(54) BACKPACK

(71) Applicant: Shenzhen Huayi Network Co., Ltd.,
Shenzhen (CN)

(72) Inventor: Dehua Ren, Shenzhen (CN)

() Term: 15 Years

(21) Appl. No.: 29/993,462

(22) Filed: Mar. 14, 2025

(51) LOC (15) Cl. 03-01

(52) U.S. Cl.

USPC D3/217
